UNITED STATES PATENT OFFICE.

WILLIAM GUTENKUNST AND CHARLES A. GUTENKUNST, OF MILWAUKEE,
WISCONSIN.

HAY-CARRIER.

SPECIFICATION forming part of Letters Patent No. 790,891, dated May 30, 1905.

Application filed September 24, 1904. Serial No. 225,867.

To all whom it may concern:

Be it known that we, WILLIAM GUTENKUNST and CHARLES A. GUTENKUNST, citizens of the United States, residing at Milwaukee, county 5 of Milwaukee, and State of Wisconsin, have invented new and useful Improvements in Hay-Carriers, of which the following is a specification.

Our invention relates to improvements in 10 hay-carriers; and it pertains more especially, first, to the peculiar mechanism for locking the carrier at a fixed point to and releasing it from its supporting-bracket both automatically and manually; second, to the mechanism 15 for automatically releasing the hay-supporting tackle-block from the carrier both automatically and manually—automatically by contact of the tackle-block with the releasing mechanism of the carrier when the same is interlocked with the carrier-retaining bracket 20 and manually when the carrier is upon either side of the retaining-bracket, as may be required when removing hay from a hay-mow or when desirous to lower the tackle-block for 25 any purpose.

Our invention is explained by reference to the accompanying drawings, in which—

Figure 1 represents a side view of the carrier upon its supporting-track, part of the carrier-frame being broken away to disclose the interior. Fig. 2 is a side view of the carrier, the carrier-supporting track, the carrier-retaining bracket, a hoisting-rope, and tackle-block by which a hay sling or fork is elevated. 30 Fig. 3 is a vertical section of our device drawn on line $x-x$ of Fig. 2. Fig. 4 is a front, and Fig. 5 a side, view of the mechanism by which the carrier is locked to and disengaged from the carrier-retaining bracket, the same being removed from the carrier-frame. Fig. 6 35 is a detail, part in section, of a part of the tackle-block and pulley used in connection with a hay-sling.

Like parts are identified by the same reference characters throughout the several views.

1 represents the carrier-supporting track.

2 is a carrier-retaining bracket by which the carrier is locked to the track as the tackle-block 3, with its load, is being elevated.

4 is a hoisting-rope.

The carrier proper comprises the carriage 5 and the frame 6 with its locking and releasing mechanism. The carriage 5, including the frame A and frame-supporting rollers B, is permanently supported upon and in the 55 same relative position to the track, while the frame 6, with the locking and releasing mechanism, is revolvably suspended from the frame 5, whereby the carrier may be reversed and run in either direction upon either side of the 60 retaining-bracket 2.

The carrier 5 is automatically locked in engagement with the bracket 2 by the retaining-catch 6', which catch is adapted to enter the retaining-recess 7 of the bracket and be automatically engaged by and between the shoulders 8 as the carrier moves horizontally along the track above said bracket. The catch 6' is pivotally supported from its retaining-bearings 9 upon the pivotal bolt 10, which 70 bolt is so located at one side of the center of gravity of said catch that the upper arm of said catch is caused to bear against the vertical surface of the diagonal plates 11 until it reaches the open recess 7, when it drops of its 75 own gravity into said recess between said retaining-shoulders 8. The retaining-catch 6' is adapted to be disengaged from said recess 7 in two different ways—first, by contact of the tackle-block with the buffering-bar 12 as the 80 load is being raised, and, second, by the operator when drawing upon the operating-cord, as hereinafter described. Motion is communicated from the buffering-bar 12 to said catch 6' through the arm 18, whereby said catch is 85 thrown back out of engagement with the carrier-retaining bracket. The catch 6' is disengaged from said bracket manually at any time before the load is raised or before the tackle-block is brought in contact with said buffering-bar by drawing downwardly upon the cord 15. Motion is communicated from the cord 15 to the catch 6' through the lever 16, pivotal connection 17, buffering-bar 12, and contact-arm 18. The contact-arm 18 forms an integral part of the catch 6', which parts are centrally pivotally supported upon the bolt 10, whereby as said arm 18 is thrown upwardly by the buffering-bar said catch 6' is thrown outwardly and away from the retaining-bracket. 90 95 100

- It will be understood that with hay-carriers as ordinarily constructed it is necessary for the tackle-block and load to be elevated to and brought in contact with the locking mechanism of the carrier regardless of the height of the mow or place of deposit, that the locking mechanism of the carrier may be disengaged from the retaining-bracket by contact of such parts. Thus it will be obvious that when 5

while the exterior collar 29 is formed integrally with the frame 6, the lower edge of the collar 29 being adapted to bear and turn upon the horizontal flange 30 of said collar 28.

5 31 represents one of the arms of the tackle-block, which is provided with a hook 32, which is adapted to engage one of the loops of a sling when the same is used in connection therewith. A similar arm 33 is formed in connection with a pulley 34, which is adapted to engage the opposite loop of the same.

10 Referring to Fig. 5, the carrier-retaining bracket comprises, in addition to the angular plates 11, which actuate the carrier-retaining catch 6', the vertical connecting-plate 35 and fastening-bolts 36. The plate 35 serves as a contact-bearing for the arm 21 of the latch 20 and holds said arm 22 and catch-actuating bar 14 in their raised position, while the catch 6' 15 is permitted to drop of its own gravity into its locking position beneath said plate.

15 It will be understood that one end of the hoisting-rope 4 is permanently secured above one of the rope-supporting pulleys 38 by a knot 39 or any equivalent stop, while the central portion of said hoisting-rope is adapted to be drawn over the opposite pulley 40, that as the end of the rope is drawn down over said pulley 40 in the act of raising the tackle-block 20 the clamping-arm 19 will be thrown back therefrom and the rope is free to pass beneath it, when by the reverse movement of said rope as the tackle-block descends said clamping-arm 19 will be drawn down by contact with the rope and be caused to impinge against it, whereby the rope is securely clamped between said clamping-arm and said pulley 40, and the tackle-block, with its load, will be suspended by the rope until said clamping-arm 19 is disengaged therefrom either by the manual act 25 of the operator by drawing down upon the operating-cord 15 or automatically by contact of the tackle-block with the lower end of the buffering-bar as the tackle-block is raised.

30 45 Having thus described our invention, what we claim as new, and desire to secure by Letters Patent, is—

1. In a hay-carrier, the combination of a carrier-retaining catch adapted to be raised by 50 sliding contact with the carrier-retaining bracket and to drop into locking engagement with said bracket when the carrier is beneath the same; means including a buffering-bar actuated by the tackle-block of the carrier as it is raised, for disengaging said catch from the retaining-bracket and additional means comprising an operating-lever pivotally connected near its center to the carrier, one end of said lever being connected with the buffering-bar and the other end with an operating-cord and means for automatically clamping the hoisting-rope by which the tackle-block is raised and preventing said tackle-block from descending from the carrier when the latter is disengaged 55 from the carrier-retaining bracket, either automatically, or manually, substantially as set forth.

2. In a hay-carrier, the combination of a carrier-retaining catch and a rope-releasing latch, 60 both pivotally supported from the carrier and

both being adapted to be raised by sliding contact with the carrier-retaining bracket as the carrier is brought into locking position with said bracket; a clamping-arm adapted to automatically engage the hoisting-rope when the 70 carrier is out of locking position with said bracket; means actuated by said rope-releasing latch for raising said clamping-arm and releasing said hoisting-rope as said latch is raised by contact with said bracket, while said carrier-retaining catch is permitted to simultaneously drop into engagement with said carrier-retaining bracket.

3. In a hay-carrier, the combination of a carrier-retaining catch; a rope-releasing latch, 80 both pivotally supported from the carrier and both being adapted to be simultaneously raised by sliding contact with the angular bearings of the carrier-retaining bracket as the carrier is brought into locking position with said bracket; a clamping-arm adapted to automatically engage the hoisting-rope when the carrier is out of locking position with said bracket; means actuated by said rope-releasing latch for raising said clamping-arm and releasing 85 said hoisting-rope as said latch is raised by contact with said bracket and additional means for manually raising said latch and releasing said clamping-arm when said carrier is out of locking engagement with said bracket, substantially as set forth.

4. In a hay-carrier, the combination of a carrier-retaining catch adapted to be raised by 90 sliding contact with the carrier-retaining bracket and to drop into locking engagement with said bracket when the carrier is beneath the same; means including a buffering-bar actuated by the tackle-block of the carrier as it is raised, for disengaging said catch from the retaining-bracket; additional means for manually releasing said catch from said bracket before the tackle-block is raised comprising an operating-lever pivotally connected near its center to the carrier, one end of said lever being connected with the buffering-bar and the other end with an operating-cord and means for automatically clamping the hoisting-rope by which the tackle-block is raised and preventing said tackle-block from descending from the carrier when the latter is disengaged 95 from the carrier-retaining bracket, either automatically, or manually, substantially as set forth.

5. In a hay-carrier, the combination of a carrier-retaining catch and a rope-releasing latch, 100 both pivotally supported from the carrier and both being adapted to be raised by sliding contact with the carrier-retaining bracket as the carrier is brought into locking position with said bracket; a clamping-arm adapted 105 to automatically engage the hoisting-rope when the carrier is out of locking position with said bracket; a buffering-bar slidably suspended beneath the center of the carrier-frame adapted to be raised by contact with 110

115 120 125 130

the tackle-block as the latter is raised, while the upper end of said buffing-bar is adapted as it is raised, to be brought in contact with the lower end of the carrier-retaining latch, 5 whereby said latch and carrier are disengaged from said bracket.

6. In a hay-carrier, the combination of a carrier-retaining catch and a rope-releasing latch, both pivotally supported from the carrier and 10 both being adapted to be raised by sliding contact with the carrier-retaining bracket as the carrier is brought into locking position with said bracket; a clamping-arm adapted to automatically engage the hoisting-rope when the 15 carrier is out of locking position with said bracket; a buffing-bar slidably suspended from the frame of the carrier; a catch-actuating bar slidably supported within said buffing-bar and adapted to engage at its upper end with the 20 lower arm of said rope-releasing latch, said buffing-bar being adapted to be raised automatically by contact with the tackle-block as it is raised, and manually through an operating-lever and lever-actuating cord, said catch- 25 releasing bar being adapted to be raised by the action of said buffing-bar, said buffing-bar being adapted, as it is raised, to contact with the lower arm of said retaining-catch, thereby releasing the same from the carrier-retaining 30 bracket, while the lower arm of said catch is adapted to contact with the lower arm of said rope-releasing latch, motion being communicated from the lower arm of said latch through said catch-actuating bar to the clamping-arm, 35 whereby the latter is thrown out of contact with the hoisting-rope and said rope is released as the carrier is disengaged from the retaining-bracket, substantially as set forth.

7. The combination of a carrier-supporting 40 track, a track-supporting bracket comprising two bearing-plates formed at an angle to said track and a central connecting-plate formed in line with said track; a carrier comprising a carriage suspended by rollers from said

track; a carrier-frame having annular swivel 45 connections with said carriage and a central vertical opening within said swivel connections for the reception of the latch and catch actuating mechanism; a buffing-bar slidably supported within said swivel connections, 50 adapted to be raised by contact with the tackle-block; a catch-actuating bar slidably supported within said buffing-bar and adapted to be actuated by the lower arm of said latch as the latter is actuated; a clamping-bar adapted 55 to engage the hoisting-rope; means for communicating motion from said catch-actuating bar to said clamping-bar as the former is raised and means for manually operating said buffing-bar when not in contact with the tackle-block, all substantially as, and for the purpose specified.

8. A carrier-retaining bracket comprising two bearing-plates formed at an angle to its supporting-track; a latch-retaining recess located between said bearing-plates; a connecting-plate located between said angular bearing-plates and formed in line with the bracket-supporting track, in combination with a hay-carrier provided with a pivotally-supported 70 catch and latch, both of which are adapted to be raised by contact with the angular bearing-plates, said catch being adapted to drop into engagement with said bracket between the ends of said angular plates while said latch 75 is held in its raised position by contact with the central connecting-plate of said bracket, whereby the carrier is locked to the bracket and the hoisting-rope is simultaneously disengaged from its clamping-arm, substantially as set forth.

In testimony whereof we affix our signatures in the presence of two witnesses.
